UNITED STATES PATENT OFFICE.

LEWIS G. MCCLINTOCK, OF PITTSBURGH, PENNSYLVANIA, ASSIGNOR TO PITTSBURGH TRANSFORMER COMPANY, A CORPORATION OF PENNSYLVANIA.

TRANSFORMER.

Application filed October 11, 1921. Serial No. 507,122.

To all whom it may concern:

Be it known that I, LEWIS G. MCCLINTOCK, a citizen of the United States, residing at Pittsburgh, in the county of Allegheny and 5 State of Pennsylvania, have invented certain new and useful Improvements in Transformers, of which the following is a specification.

This invention relates to transformers and 10 particularly to transformers immersed in oil in a tank. In such structures it is highly important to hold the transformer from shifting in the tank and also to brace the tank against shocks, for the holding means 15 is objectionable if it involves a relative stressing between the parts of the tank such as the sheet metal sides and bottom plate. At the same time it is desirable to have different sizes of transformers and tanks 20 interchangeable so that a given transformer may be fitted in different sizes of tanks and vice versa to have a given tank readily adaptable for different transformers.

The structure of this invention provides 25 for the accurate positioning and holding of the transformer in the tank and protects the tank walls against weakening stresses in service and transportation. At the same time the holding means is readily adaptable 30 for various sizes of transformers so as to give a wide interchangeability of transformers and tanks.

In the accompanying drawings illustrating the invention—

35 Fig. 1 is a vertical sectional view of a transformer and tank with parts broken away, and

Fig. 2 is a diagrammatic plan view of the 40 transformer holding means at the bottom.

In the specific embodiment of the invention shown in the drawings a base B carries a tank K in which is the transformer T. Tie rods 5 are provided extending from the base B through eyelets 6 at the top of the 45 transformer and the base, tank and transformer are lifted as a unit by these tie rods. The tank K has its bottom plate 8 flanged upward at 9 and welded at 10 to the lower 50 end of the body 11 forming the corrugated side walls of the tank, these sides being usually made of relatively thin sheet steel.

The transformer T is set on this bottom plate 8 which in turn rests on the base B so that the weight of the transformer is 55 transmitted directly to the base. To hold

the transformer in place a frame of angle bars 15 is fastened to the bottom 8 preferably by welding their horizontal flanges to the bottom. These angle bars 15 have their horizontal flanges 16 facing outward and 60 their vertical flanges 17 forming a rectangle or other shape adapted to fit and hold the transformer frame F set into it. To insure that frame F will drop into place within the angle bar strips as it is lowered, 65 guide members 18 are provided welded to the angle bars and inclined outward from the upper edges thereof to form guides for the frame F as it is lowered into place. These angle bars or stops 15 prevent the 70 transformer from shifting on the bottom plate 8 and receive the lateral thrusts. There is no contact between the transformer and sides or body 11, the transformer being 75 securely held to the center of the bottom 75 plate 8 by the stops 15 which do not connect to the tank sides but are independently fastened in place on the tank bottom. The tank body 11 is thus relieved of any side stresses 80 or thrusts from the transformer which is anchored firmly in place by the bottom structure independently of the tank sides.

To hold the transformer T securely against the tank bottom and also to hold the upper part of the tank against sidewise strains screw posts 20 are carried upward from the braces between vertical corner members 21 of frame F on the heavy transformer core, and these posts carry nuts, 85 adapted to press upward on the transformer cover 22 and downward on the bottom plate 8. The cover 22 is clamped at its edges to the top flange of the tank body 11 and in this way the transformer is vertically gripped 90 between the cover and the bottom of the tank, while laterally it is held secure by the stops 15 directly transmitting any side thrusts to the bottom plate. The tank sides are protected against excessive stresses and 95 these sides and the weld between the sides with the bottom remain intact and secure against weakening in service. This avoids the danger of leakage and even permits the whole transformer to be shipped in assembled condition with oil in the tank. 100

The holding frame may be made of any desired size within the limits of the tank frame 15 so as to readily adapt the tank for smaller or larger transformers simply by 110 forming the frame to fit the desired size

of transformer. A given size of tank is thus easily fitted to different sizes of transformers without alteration of the transformer structure. This enables separate stocks of tanks and transformers to be assembled in widely variant manner and avoids the necessity of forming the transformer structure to fit a particular size of tank.

10 I claim:—

1. The combination with a transformer, of a tank therefor having a sheet metal body formed of sides and an imperforated bottom plate and separate stop members fastened on said plate and adapted to retain said transformer spaced from the sides of said tank, said stop members also being spaced from the sides of said tank and being adapted for attachment to said plate in positions to accommodate various sizes of transformers.

2. The combination with a transformer, of a tank therefor having a sheet metal body comprising sides and a bottom plate welded thereto, said bottom plate laterally of said transformer being curved upwardly toward its welded connection with the sides and stop members fastened to said bottom plate and spaced from the sides and adapted to retain said transformer spaced from the sides.

3. The combination with a sheet metal tank having sides and a bottom welded there-

to, of a transformer in said tank spaced from said sides, separate angle members 25 welded to said bottom and spaced from said sides, said members serving to retain said transformer in position in said tank and being formed with inclined guiding portions to assist in seating said 40 transformer in position.

4. The combination of a base, a sheet metal tank on said base, said tank having sides and a bottom welded thereto, a transformer in said tank spaced from said sides, 45 a cover for said tank means connecting said transformer and cover and adapted to press upwardly on said cover means connecting said base and cover and adapted to press downwardly on said cover and means secured to the bottom of said tank and spaced from the sides for retaining said transformer in position.

5. The combination with a transformer of a tank therefor having corrugated sheet 55 metal sides and a bottom plate in abutting contact with the lower portion of said sides and welded thereto, means for supporting said transformer tank along said bottom plate and means for rigidly securing said 60 transformer to the central portion of said bottom plate, said bottom plate laterally of said transformer being peripherally arched and free to bend under lateral and vertical stresses.

LEWIS G. McCLINTOCK.
